[57] CLAIM

The ornamental design for a moisture retaining head band for use in permanent waving, as shown and described.

DESCRIPTION

FIG. 1 is a front elevational view of the moisture retaining head band for use in permanent waving showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an isometric view; and,

FIG. 8 is an elevational view shown in use.

The broken line showing of the human figure and hair rollers in FIG. 8 is for illustrative purposes only and forms no part of the claimed design.

FIG. 1

FIG. 2

FIG. 3

FIG. 4.

FIG. 5

FIG. 6

FIG. 7

FIG. 8
